UNITED STATES PATENT OFFICE.

IVAR JOHAN EDWARD ÅGREN, OF UPSALA, SWEDEN.

METHOD OF PRODUCING EMBOSSED METAL WORK.

Specification of Letters Patent. Patented Sept. 17, 1918.

1,278,816.

Application filed March 19, 1918. Serial No. 223,477.

To all whom it may concern:

Be it known that I, IVAR JOHAN EDWARD ÅGREN, a subject of the King of Sweden, residing at Upsala, Sweden, have invented 5 new and useful Improvements in Methods of Producing Embossed Metal Work, of which the following is a specification.

The present invention relates to a method of producing embossed or chased metal 10 work, and more particularly that work which is composed of copper.

An object of the invention is the provision of a method of the above-described character wherein the cost of manufacture of 15 embossed metal work is materially reduced without sacrificing its artistic quality.

Another object of the invention is a method of producing embossed metal work, whereby the metal work can be produced in 20 large quantities from a single pattern without the use of a special machine.

The characteristics of the invention consist in pressing a thin lead-plate or the like upon a negative in such a manner that the 25 lead-plate itself will form a positive, perforating the plate and then furnishing such a positive by means of galvano-plastics, with a rather thick lining on both sides. When a lead, tin or such like plate is employed, it is primarily furnished in a bath 30 of hydrocyanate of potash with a thin lining of, for instance, copper, before the galvano-plastic precipitation is made. By first perforating the lead-plate and then forming 35 a copper lining on both sides of the plate, a portion of the copper of each lining is deposited in the perforations, thus rigidly connecting the two linings and forming a strong 40 connection between the copper and the lead-plate. The plate thus composed will offer the greatest possible resistance to bending stresses and the like, while employing the least possible amount of copper.

In order to get a suitable negative for the 45 method in question, a positive of lead-plate, copper, or the like, made by hand can be

produced and after this the positive is furnished by means of galvano-plastic with a thick lining, a solid bed being then cast upon the lining and the positive being torn 50 off or removed so that the desired negative will be exposed. The said negative is especially adapted for pressing such a soft material as lead upon the negative, and this 55 pressing is preferably effected by hand.

In the accompanying drawings, Figure 1 is an elevation of a plate made in accordance with the present invention. Fig. 2 is a vertical sectional view of the same, taken 60 on the line 2—2 of Fig. 1.

A designates the positive plate formed with a number of perforations *a* extending transversely through the plate. B and B' 65 designate the relatively thick copper linings which are disposed upon opposite sides of the plate A and which, as shown in Fig. 2, have portions thereof filling the perforations *a* so that the linings are rigidly connected to each other and to the plate.

The invention is especially intended for 70 the production of artistically ornamental electric armature, but, of course, it can be employed for many other purposes.

What I claim is:

A method of producing embossed metal 75 work which consists in forming a positive plate composed of soft metal by pressing the plate upon a negative in such a manner that the plate itself will form a positive, perforating the plate, and then forming a 80 comparatively thick lining of metal on both sides of the plate by means of galvano-plastics, and depositing a metal in the perforations of the plate.

In testimony whereof I have signed my 85 name to this specification in the presence of two subscribing witnesses:

IVAR JOHAN EDWARD ÅGREN.

Witnesses:

J. F. A. RUTBATK,
JACOB BAGGS.
